US0D1105438S

(12) **United States Design Patent** (10) **Patent No.:** **US D1,105,438 S**
(45) **Date of Patent:** **** Dec. 9, 2025**

(54) **MEDICAL GAUZE**

(71) Applicant: **Good Gauze, LLC**, Jackson, WY (US)

(72) Inventor: **Elizabeth Catalano**, Pelham Manor, NY (US)

(73) Assignee: **GOOD GAUZE, LLC**, Jackson, WY (US)

(**) Term: **15 Years**

(21) Appl. No.: **29/987,049**

(22) Filed: **Jan. 21, 2025**

Related U.S. Application Data

(63) Continuation of application No. 29/928,799, filed on Feb. 15, 2024, now Pat. No. Des. 1,065,519, and a continuation of application No. 29/928,796, filed on Feb. 15, 2024, now Pat. No. Des. 1,065,517, and a continuation of application No. 29/928,797, filed on Feb. 15, 2024, now Pat. No. Des. 1,065,518, and a continuation of application No. 29/928,793, filed on Feb. 15, 2024, now Pat. No. Des. 1,065,516, and a continuation of application No. 29/928,767, filed on Feb. 15, 2024, now Pat. No. Des. 1,065,515, said application No. 29/928,796 is a continuation of application No. 29/755,779, filed on Oct. 22, 2020, now Pat. No. Des. 1,024,320, which is a continuation of application No. 29/671,791, filed on Nov. 29, 2018, now abandoned.
